UNITED STATES PATENT OFFICE.

FREDERICK KOPF, OF MEMPHIS, TENNESSEE.

HORSESHOE-PAD.

1,131,064.

Specification of Letters Patent.

Patented Mar. 9, 1915.

Application filed January 11, 1915. Serial No. 1,482.

To all whom it may concern:

Be it known that I, FREDERICK KOPF, a citizen of the United States, residing at Memphis, in the county of Shelby and State 5 of Tennessee, have invented certain new and useful Improvements in Horseshoe-Pads, of which the following is a specification.

My invention relates to improvements in horseshoe pads in which a cushion is provided and in which the various parts are 10 connected together in such a manner that they will not be liable to become disconnected.

The objects of my invention are, first, to 15 provide a horseshoe pad that will be light and one that will protect the tender parts of the horses' feet; and second, to provide a shoe that will be light and at the same time not liable to injure the limbs of the horse. 20 These objects, together with other objects readily apparent to those skilled in the art, I attain by the construction illustrated in the accompanying drawings, although my invention may be embodied in a variety of 25 other mechanical forms, the construction illustrated being chosen by way of example.

In the accompanying drawing: Figure 1 is a bottom view of a horseshoe embodying my invention. Fig. 2 is an end view showing the heel end of the shoe. Fig. 3 is a section taken on line 3—3, Fig. 1, some of the parts being shown enlarged to more clearly illustrate the assembled parts. Fig. 4 is a detached view of the inlaid plate located in the heel portion of the shoe. 35

Similar numerals of reference indicate corresponding parts throughout all the figures of the drawing.

In the accompanying drawing, 1 represents the shoe which is of the usual shape, except that the heel end is formed of less length than the pad proper. Upon the upper face or side of the shoe is located the elastic pad 2, which elastic pad is extended 40 beyond the heel ends of the shoe 1 and is provided with the heel calks 3, which heel calks may be formed integral with the pad 2 and their outer edges curved to correspond substantially with the curvature of the metal 45 shoe 1, whereby the general shape of the shoe from heel to toe is maintained, regardless of the fact that the metal shoe 1 is formed shorter. The heel calks 3 are held in proper relative position with reference

to each other by means of the tie member 4, which tie member is substantially of the form shown in Fig. 1. It will be understood that by forming the heel end of the shoe as above described that the metal shoe can be formed very light, thereby reducing the 60 weight of the shoe, and at the same time providing means whereby sudden jars are largely reduced in violence.

For the purpose of preventing the heel portion of the horseshoe proper from undue 65 bending or accidental detachment I provide the metal plate 5, which metal plate is inlaid in the tie member 4 and portions of the calks 3, said plate being extended toward the toe end of the shoe and inlaid in the 70 pad portion located over the shoe 1. By this arrangement the rubber or elastic or cushioned heel portion of the shoe is given sufficient rigidity, but at the same time allowing sufficient elasticity to prevent injury 75 to the horse, and at the same time prevents the elastic or rubber portion from becoming displaced by the sudden stopping of the horse when going at a rapid rate.

Directly above the pad 2 is located the 80 pad section or member 6, which is preferably formed of leather, but not necessarily so as the only object is to provide a pad that will have sufficient elasticity and at the same time protect the bottom or sole of the 85 foot. Upon the top of the pad 6 is attached the sheepskin 7, said sheepskin having thereon the natural wool 8 which forms a soft surface for the bottom of the foot or more specifically for the frog of the horse's 90 foot.

From experience I have learned that by the use of oakum or cotton placed next to the foot it is liable to become displaced, thereby causing lameness and injury, but by 95 leaving the natural wool upon the sheepskin, the above pointed out difficulty is overcome, owing to the fact that the wool is held in place and is not permitted to be shifted from its original position. In order to 100 assist in protecting the rubber or elastic portion of the shoe at the heel end of the same, the tie member 4 and the rubber or pad portion extended toward the toe is beveled, the beveled sides extended inward, whereby the 105 rubber or elastic portion is better protected. Another object in providing the inward beveled portions is to give sufficient thick-

ness and rigidity to the pad 2 and at the same time give better protection.

Having fully described my invention what I claim as new and desire to secure by Letters Patent, is—

1. A horseshoe pad of the class described, comprising a metallic shoe formed of a length less than the length of the shoe proper, an elastic pad located upon the upper face of the shoe, said pad extended beyond the heel ends of the shoe and provided with heel calks, a metal plate inlaid in the heel calks and pad, a second pad located upon said pad having the inlaid plate and a pad having located thereon wool secured to said second pad.

2. In a horseshoe pad of the character described, the combination of a metallic shoe, a pad provided with heel calks, said pad formed of a size and shape to correspond with a horse's foot, a metallic plate located in the heel portion of the pad, a sheepskin pad located above the pad provided with the heel calks and upon the upper side of the shoe.

3. In a horseshoe pad, the combination of a metallic horseshoe, a pad located upon said horseshoe and adapted to cover the bottom of a horse's foot, said pad provided with heel calks, said heel calks located beyond the heel ends of the metal shoe, a metal plate secured to the pad provided with the heel calks, said metal plate extended beyond

the heel ends of the metal shoe and embedded in the heel calks.

4. In a horseshoe pad, the combination of a metallic horseshoe, a pad located upon said horseshoe and adapted to cover the bottom of a horse's foot, said pad provided with heel calks, said heel calks located beyond the heel ends of the metal shoe, a metal plate secured to the pad provided with the heel calks, said metal plate extended beyond the heel ends of the metal shoe and embedded in the heel calks, and in the heel calk tie member.

5. In a horseshoe pad, the combination of a metallic horseshoe, a pad located upon said horseshoe and adapted to cover the bottom of a horse's foot, said pad provided with heel calks, said heel calks located beyond the heel ends of the metal shoe, a metal plate secured to the pad provided with the heel calks, said metal plate extended beyond the heel ends of the metal shoe and embedded in the heel calks and in the heel calk tie member, and a sheepskin having the natural wool located thereon, adapted for contact with the sole of a horse's foot.

In testimony that I claim the above, I have hereunto subscribed my name in the presence of two witnesses.

FREDERICK KOPF.
